PHYSICIAN'S EXAMINING CHAIR

William B. Hall, Upper Montclair, N.J., and Ernest F. Thomson, New York, N.Y., assignors to Shampaine Company, St. Louis, Mo., a corporation of Missouri

Filed Sept. 11, 1959, Ser. No. 57,511

Term of patent 14 years

(Cl. D83—1)

FIG. 1.

FIG. 2.

FIG. 4.

FIG. 3.

FIG. 1 is a right side elevation of a physician's examining chair embodying our new design;

FIG. 2 is a left side elevational view thereof;

FIG. 3 is a front elevational view thereof; and

FIG. 4 is a perspective thereof.

The rear of the backrest portion is substantially plain.

We claim:

The ornamental design for a physician's examining chair, substantially as shown and described.
